BRAKE

Geoffrey Robert Greenbergh Gates, Leamington Spa, England, assignor to Automotive Products Company Limited, Leamington Spa, England

Application March 20, 1941, Serial No. 384,409
In Great Britain April 5, 1940

2 Claims. (Cl. 188—152)

This invention relates to internal shoe brakes of the type comprising two substantially rigid arcuate shoes pivotally mounted on a common anchorage abutment or on adjacent abutments, and a spreading device between the un-anchored ends of the shoes. In brakes of this type, one of the shoes, when applied to the drum, tends to be urged more firmly into engagement with the drum by the rotation of the latter, and is commonly referred to as the leading shoe, whilst the other shoe, commonly referred to as the trailing shoe, tends to be urged away from the drum by the rotation of the latter, the leading shoe being that shoe along which a point on the drum surface travels from the spreading device to the anchored end. The brake, according to the present invention, is intended for use on a motor road vehicle which travels almost exclusively in one direction, being only occasionally driven in the reverse direction, and the brake shoes which are referred to herein as the leading shoe and trailing shoe respectively are those which act in those capacities when the vehicle is travelling in its normal direction.

The principal object of the invention is to provide an improved means of adjusting the shoes of a brake of the type referred to, to compensate for wear of the friction surfaces.

According to the invention, the spreading device, which is mounted for longitudinal sliding movement between the shoe ends, forms a rigid spacer for said shoe ends when the brake is not applied, and an adjusting means is provided for moving the trailing shoe outwardly into contact with the drum, the said shoe being subsequently spaced from the drum to a small extent by the distortion of the drum when the brakes are applied with the vehicle in motion, thus moving the spreading device towards the leading shoe to centralize the shoes in the drum.

According to another aspect of the invention, the spreading device, which is mounted for longitudinal sliding movement between the shoe ends, forms a rigid spacer for the said shoe ends when the brake is not applied, and an adjusting means is provided which acts on the leading shoe, and, through the spreading device, on the trailing shoe, to move both shoes outwardly into contact with the drum, the leading shoe being then spaced from the drum by reverse movement of the adjuster, and the shoes being centred by the distortion of the drum when the brakes are applied with the vehicle moving in a forward direction.

The adjusting device may be disposed between the spreading device and one of the shoes, and the spreading device may be a fluid pressure wheel cylinder. The wheel cylinder may comprise an open ended cylinder in which operate opposed plungers whose movement into the cylinder is limited. The spreading device may com-

prise a plunger and cylinder unit capable of angular movement in the plane of the brake shoes, and pivotally engaged with the leading shoe.

The invention is hereinafter described with reference to the accompanying drawings, in which:

Figure 1 is a side elevation of a brake according to the invention;

Figure 2 is a view corresponding to Figure 1, but on a larger scale, and with certain parts in section;

Figure 3 is a section on the line 3—3 of Figure 2; and

Figures 4 and 5 are diagrams showing how the brake shoes are centralized by the drum distortion.

Referring to Figures 1 to 3, a brake, the drum of which rotates normally in a clockwise direction, comprises a pair of shoes 10, 11 mounted on separate anchor pins 12, 13 on a back plate 14 and a liquid pressure wheel cylinder 15 mounted on the back plate between the un-anchored ends of the shoes. The shoe 10 is normally the trailing shoe, and the shoe 11 the leading shoe. The wheel cylinder 15 is formed with a spigot 16 projecting in a direction perpendicular to its bore 17, which spigot passes through a hole 18 in the back plate and is retained in position by a spring ring 20 between which and the back plate is a washer 21 of friction material. The hole 18 through which the spigot passes is elongated in the direction of the axis of the wheel cylinder 15, so that the latter is capable of both rotary and translational movement, such movement being resisted to a slight degree by the friction between the washer 21 and the back plate. In the cylinder 15 are mounted two opposed pistons 22 and 23 provided with suitable fluid-tight packings 24. The piston 22 which acts on the trailing shoe 10, is solid, and is formed at its outer end with an annular flange 25 adapted to engage with the end of the cylinder 15 and limit the movement of the piston into the cylinder. The outer end surface 26 of the piston is flat, and is engaged by the arcuate edge of a projection 27 formed on the web of the trailing shoe 10. The second piston 23 is deeply recessed from its outer end at 28 to receive the threaded end of an adjusting plunger 30 threaded into the base of a cap 31 fitting slidably over the end of the wheel cylinder 15, the base of the cap 31 being adapted to engage both the end of the cylinder 15 and the end of the piston 23. The outer end of the adjusting plunger 30 is enlarged to form a head 32, and is slotted at 33 to embrace a projection 34 on the leading shoe web similar to the projection 27 on the trailing shoe, the base of the slot 33 being of concave arcuate form to correspond to the shape of the projection 34. The plunger 30 is thus restrained against rotation by the web of the shoe. The edge of the cap 31 is turned outwardly, and formed with a series of notches 35

to co-operate with a spring finger 36 mounted on the cylinder, the cap being rotatable on the cylinder by engaging a tool in the notches 35, but being held against free rotation by the spring finger 36. A pull-off spring 37 extends between the two shoes and maintains them in contact with the two plungers in the wheel cylinder.

The brake shoes 10 and 11 are expanded into contact with the drum 38 by liquid under pressure entering the wheel cylinder 15 between the two pistons 22 and 23, the piston 22 associated with the trailing shoe 10 acting directly on that shoe, whilst the piston 23 associated with the leading shoe applies an outward thrust to the cap 31, such thrust being transmitted through the adjusting plunger 30 to the shoe 11.

The arcuate slot 33 on the plunger 30, by its engagement with the projection 34 on the leading shoe 11, causes the wheel cylinder 15 to follow the movements of the leading shoe, the centre of curvature of the projection 34 remaining always on the longitudinal axis of the wheel cylinder 15, which axis thus tends to turn slightly about the mounting spigot 16 of the cylinder as the shoe 11 moves. The pressure is thus always transmitted to the leading shoe along the longitudinal axis of the cylinder, and no side loads are applied to the piston 23.

As the piston 22 is flanged at 25 to engage one end of the wheel cylinder, and the cap 31 in which the adjusting plunger 30 is mounted engages the other end of the wheel cylinder, the cylinder, when the brakes are "off," forms a rigid spacer for the shoes and limits their movement away from the drum. The location of the shoes is thus dependent on the position of the wheel cylinder.

Adjustment of the shoes to reduce the clearance between the linings and the drum when the former have worn down is effected by rotating the cap 31 on the wheel cylinder, to cause the adjusting plunger 30 threaded thereinto to move outwardly. Such outward movement first of all brings the leading shoe 11 into contact with the drum 38, and then causes the cylinder 15 to move in the opposite direction, taking with it the trailing shoe piston 22, the flange 25 of which remains in engagement with the end of the wheel cylinder, until the trailing shoe 10 also engages the drum 38. The adjusting plunger 30 is then withdrawn slightly by rotating the cap 31 in the reverse direction to provide a slight clearance between the leading shoe 11 and the drum 38, the cylinder 15 being held in its new position by the friction between the washer 21 and the back plate, so that the trailing shoe 10 remains in contact with the drum. The vehicle is then set in motion in the forward direction, and pressure applied to the pistons 22 and 23 in the wheel cylinder. As the trailing shoe is already in contact with the drum, only the piston 23 is moved outwardly, and the distortion of the drum due to the greater pressure of the leading shoe 11 causes the end of the trailing shoe 10 adjacent the wheel cylinder to move inwardly, thus moving the wheel cylinder 15 slightly in the direction of the leading shoe to distribute the clearance between the two shoes. It has been found that, with a brake comprising a leading and a trailing shoe the drum tends to distort during brake application to a somewhat elliptical form, with its major axis through the drum centre and the approximate centres of the shoes, and its minor axis spaced slightly from the true drum centre towards the leading shoe. This distor-

tion is shown by the full-line position of the drum in Figure 5, which is of course much exaggerated, and by comparison with Figure 4 it can be seen that the trailing shoe 10 is in substantially the same position when engaged with the distorted drum as when free with the drum concentric with the back plate. The clearance obtained at the trailing shoe tip is of course equal to the displacement of the drum due to distortion at this point, and proper centralization of the shoes is obtained by slackening back the adjuster, after both shoes have touched the drum, until the leading shoe tip clearance is twice that given at the trailing shoe tip by the drum distortion. The trailing shoe, having been in engagement with the drum whilst the latter was undistorted, will have its end nearer to the wheel cylinder moved inwardly when, owing to the application of the brakes, the drum is distorted, thus producing the slight movement of the wheel cylinder required to centralize the shoes.

A thin metal cap 39 extending over the wall of the cylinder 15 is attached to the piston 22 operating the trailing shoe, to prevent the entry of dust and water into the cylinder.

What I claim is:

1. In a brake having a trailing shoe and a leading shoe, a spreading device which is frictionally mounted for longitudinal sliding movement and for angular movement between the shoe ends and which forms a rigid spacer for said shoe ends when the brake is not applied, said spreading device comprising an open-ended fluid pressure wheel cylinder having opposed plungers operating therein and having means for limiting the inward movement of the plungers, and adjusting means at one end of the spreading device and pivotally engaged by the end of the leading shoe and operable for moving the trailing shoe outwardly into contact with the drum, the said shoe being subsequently spaced from the drum to a small extent by the distortion of the drum when the brakes are applied with the vehicle in motion, thus moving the spreading device toward the leading shoe to centralize the shoes in the drum, said adjusting means comprising a screwed plunger pivotally engaged by the end of the leading shoe and adjustable relatively to one of the wheel cylinder plungers and threaded into a cap engaging the end of the wheel cylinder, said cap being adapted to be engaged on its inner face by the wheel cylinder plunger.

2. In a brake having a trailing shoe and a leading shoe, a spreading device which comprises a plunger and cylinder unit frictionally movably mounted and capable of angular movement in the plane of the brake shoes and which is mounted for longitudinal sliding movement between the shoe ends, said spreading device forming a rigid spacer for said shoe ends when the brake is not applied and pivotally engaging the leading shoe, and an adjusting means associated with the spreading device which is pivotally engaged by the end of the leading shoe and which acts on the leading shoe and through the spreading device on the trailing shoe to move both shoes outwardly into contact with the drum, the leading shoe being then spaced from the drum by reverse movement of the adjuster, and the shoes being centered by the distortion of the drum when the brakes are applied with the vehicle moving in a forward direction.
